Patented Dec. 16, 1975

238,065

PLAYING SURFACE MODULE FOR ATHLETIC
ACTIVITIES SUCH AS TENNIS COURTS, SWIM-
MING POOL AREAS, AND THE LIKE

Wilfred G. Harvey, 42 Sullivan Way,
East Brunswick, N.J. 08816

Filed Sept. 29, 1972, Ser. No. 293,406

Term of patent 14 years

Int. Cl. D25—02

U.S. Cl. D13—1 J

FIG. 1

FIG. 3.

FIG. 1 is a top plan view of a playing surface module for athletic activities such as tennis courts, swimming pool areas, and the like showing my new design;

FIG. 2 is a fragmentary, perspective view of a portion, as indicated at 2 in the plan view of FIG. 1; and

FIG. 3 is a further enlarged plan view as indicated at 3 in the plan view of FIG. 1.

I claim:

The ornamental design for a playing surface module for athletic activities such as tennis courts, swimming pool areas, and the like, as shown.
